[57] ABSTRACT

An elongated wrench body is provided in its end with a V-shaped notch which defines two adjacent sides of a four-sided open socket. A removable head is positioned on the body and projects therefrom to define two parallel opposing sides of the socket. A pair of strip-like spacers are slidably interposed between the head and the opposite side edges of the body and are projectable so that they are juxtaposed to the opposing sides of the socket for adjusting the effective span of the latter. The spacers are contained in recesses formed in the body and may be removed from the recesses upon removal of the head.

OPEN-ENDED WRENCH WITH ADJUSTABLE SOCKETS

This invention relates to new and useful improvements in wrenches, and in particular the invention concerns itself with wrenches having an open-ended socket, the effective span of which may be easily adjusted by retractable and projectable spacers so that the wrench may accommodate nuts or bolt heads of different sizes.

While adjustable wrenches of this general type are known in the art, the principal object of the invention is to provide an improved construction wherein the wrench head is removably mounted on the wrench body and wherein the retractable and projectable spacers are interposed between the body and the head so that they may be easily removed for purposes of inspection or replacement upon removal of the head from the body.

The wrench of the invention is simple in construction, dependable in use, and lends itself to convenient and economical manufacture.

With the foregoing more important object and features in view and such other objects and features which may become apparent as this specification proceeds, the invention will be understood from the following description taken in conjunction with the accompanying drawings, in which like characters of reference designate like parts, and in which:

FIG. 1 is a perspective view showing one embodiment of a wrench in accordance with the invention;

FIG. 2 is an enlarged, fragmentary sectional view of one end portion thereof;

FIG. 3 is a fragmentary plan view of the subject shown in FIG. 3;

FIG. 4 is a group perspective view of the two spacers;

FIG. 5 is a fragmentary perspective view, in exploded form, showing a modified embodiment of the wrench;

FIG. 6 is a sectional view of the embodiment of FIG. 5 assembled;

FIG. 7 is a fragmentary sectional detail, taken substantially in the plane of the line 7-7 in FIG. 6; and

FIG. 8 is a fragmentary side elevational view of another modified embodiment.

Referring now to the accompanying drawings in detail, more particularly to FIGS. 1-4 inclusive, the adjustable wrench of the invention is designated generally by the reference numeral 10. The same comprises an elongated wrench body 11 which preferably is of a rectangular cross-section, having a pair of opposite side edges 11a, 11b. A pair of wrench head units 12 are provided at the opposite ends of the body 11. These units are of different sizes but are identical in construction, so that a description of one will suffice for both.

As is best shown in FIG. 2, the end of the body 11 is provided with a V-shaped notch 13 which defines two adjacent sides of a four-sided open socket 14. A removable wrench head 15 is positioned on the end portion of the body 11 and projects therebeyond so as to define two parallel opposing sides 16, 17 of the socket 14. The head 15 is removably mounted on the body 11 by a pair of screws 18 extending transversely through the head and body, as will be readily understood.

The side edges 11a, 11b of the body 11 are provided with recesses 19 which accommodate a pair of slideable strip-like spacers 20, 21. These spacers are slideable longitudinally from a retracted position wherein they are flush with the end of the body 11, as shown by the

spacer 21 in FIG. 2, to a projected position shown by the spacer 20, in which the spacers are juxtaposed to the respective opposing sides 16, 17 of the socket 14. The two spacers have different thicknesses and when they are retracted, the socket 14 has a maximum effective span. However, when either one or both spacers are projected, the effective span of the socket is correspondingly decreased to accommodate nuts or bolt heads of different sizes.

10 A finger-piece 22 is rigidly secured to the inner end of each of the spacers 20, 21, the finger-pieces projecting slidably through slots 23 formed in the head 15, so that the spacers may be easily slid between their retracted and projected positions. Each finger-piece is 15 also formed with a pair of longitudinally spaced depressions 24 for engagement by detents in the form of balls 25 which are contained in a bore 26 formed in the body 11. A compression spring 27 in the bore 26 urges the balls 25 outwardly against the spacers 20, 21 and when the balls engage either one or the other of the depressions 24 in the respective spacers, the spacers are releasably held in either their projected or their retracted position.

20 It is to be noted that upon removal of the screws 18, the head 15 together with the spacers 20, 21 may be readily removed from the body 11, since the body recesses 19 become open when the head is removed. The spacers may then be readily separated from the head. The parts, of course, may be re-assembled with equal expediency. FIGS. 5-7 illustrate a modified embodiment of the wrench designated generally as 10a. For most part this is of the same construction as the wrench 10 and corresponding reference numerals designate corresponding parts. However, the wrench 10a embodies a slightly different arrangement of the detent means for releasably retaining the spacers 20, 21 in either the retracted or projected position. Thus, in the wrench 10a, the side edges 11a, 11b of the body 11 are provided with the depressions 30 for the detent balls 31 25 located in apertures 32 in the spacers 20, 21, (see FIG. 7). The balls 31 are biased toward the body 11 and into engagement with the depressions 30 by compression springs 33 which are held in hollow finger-pieces 34.

30 Another modified embodiment is shown in FIG. 8, in which the central axis 40 of the wrench head 15 is offset by an angle, such as an angle of 12°, from the longitudinal axis 41 of the body 11' in order that the wrench may be used in poorly accessible locations. The sliding spacers in the head 15 of the embodiment of FIG. 8 35 may utilize the locking detent arrangement of either FIGS. 1-4 or of FIGS. 5-7, as desired, and apart from the angular disposition of the head, the wrench construction is otherwise the same as already described.

40 While in the foregoing there have been described and shown the preferred embodiments of the invention, various modifications and equivalents may be resorted to, within the spirit and scope of the invention as claimed.

45 What is claimed as new is:

50 1. An open-ended wrench with an adjustable socket, comprising in combination, an elongated substantially solid body provided in one end thereof with a V-shaped notch defining two adjacent sides of a four-sided open socket, a removable head telescopically positioned on 55 said one end portion of said body and projecting therebeyond to define two parallel opposing sides of said socket, detachable fastener means removably retaining

said head in position on the body, a pair of strip-like spacers interposed between said head and the respective opposite side edges of said body, said spacers being individually slidable from a retracted position wherein they are flush with the end of the body to a projected position wherein they are juxtaposed to the respective opposing sides of said socket for adjusting the effective span of the socket, and detent means for releasable retaining said spacers in their projected and retracted positions.

2. The device as defined in claim 1 wherein said opposite side edges of said body are formed with elongated recesses slidably receiving the respective spacers therein, said recesses being open to facilitate removal of the spacers therefrom when said head is removed from said body.

3. The device as defined in claim 1 wherein said means for removably retaining said head on said body comprise at least one screw-threaded fastener extending through the head into the body.

4. The device as defined in claim 1 together with finger-pieces provided on said spacers and projecting slidably through slots formed in said head.

5. A wrench with an adjustable socket, comprising in combination an elongated body including an intermediate handle portion and opposite end portions; and at least one removable head positioned on one of said opposite end portions and projecting therebeyond, said head having a narrow neck portion for connection to said one end portion of said body and an enlargement

in which a wrench socket is provided, said neck having an elongated opening extending therethrough in which said one end portion is slidably received, means removably retaining said head in position on said one end portion, said end portion having a pair of opposite parallel side edges spaced from a like pair of opposite parallel side walls in said head which extend through said neck into said enlargement and define two parallel opposite sides of said socket, a pair of strip-like spacers interposed between said head and the respective opposite side edges of said body end portion, said spacers being individually slidable from a retracted position wherein they are flush with the end of said body end portion to a projected position wherein they are juxtaposed to the respective opposing sides of said socket for adjusting the effective span of said socket, and detent means for releasably retaining said spacers in their projected and retracted positions, each of said spacers being entirely encased between a side edge of said body and a side wall of said head in retracted position.

6. The wrench set forth in claim 5 wherein said one end portion is angularly offset from said handle portion.

7. The wrench set forth in claim 5 wherein there are two removable heads positioned respectively on opposite end portions of said body, the wrench socket of the respective heads being of a different size with respect to each other.
